UNITED STATES PATENT OFFICE.

ROBERT M. WILSON, EDWARD M. SPEAR, AND MAYNARD F. PEIRCE, OF SPRINGFIELD, MASSACHUSETTS.

WHIP-CORE.

SPECIFICATION forming part of Letters Patent No. 327,746, dated October 6, 1885.

Application filed March 21, 1885. Serial No. 159,647. (No model.)

To all whom it may concern:

Be it known that we, ROBERT M. WILSON, EDWARD M. SPEAR, and MAYNARD F. PEIRCE, citizens of the United States, residing at 5 Springfield, Hampden county, and State of Massachusetts, have invented a new and useful Improvement in Whip-Cores, of which the following is a specification.

This invention relates to that class of whip-cores in which whalebone combined with rattan is used to build up a core to be subsequently plaited and otherwise covered to complete the whip; and our invention consists in forming one or more saw-kerfs in the 15 rattan, from which the core is shaped, to extend from side to side of the rattan-piece and to longitudinally coincide with its axis, and in then filling said kerf or kerfs with a corresponding strip of whalebone, and gluing 20 together the surfaces of whalebone and rattan in contact.

Heretofore in the process of strengthening and giving elasticity to the rattan cores of whips by uniting whalebone therewith it has been common to form a central core of whalebone and build up the form of the core by an envelope of rattan strips disposed thereupon; but the size of the solid whalebone core required, from the growing scarcity of the 25 material, renders it increasingly difficult to supply a whip of this class for general use. We have found that by combining strips of whalebone, as above described, with the rattan to form a core, a whip is provided having 30 the strength and elasticity of one with a solid central whalebone core, while the strips of whalebone may be no thicker than shaving-board, and may be formed of what would be waste in shaping a solid core.

40 We are aware that saw-kerfs have been used in rattan cores to make a place for rawhide strips within said core, for the purpose of strengthening the same; but the rawhide adds no elasticity to the core and exerts no 45 influence, as in the case of strips of whalebone, to keep the whip straight.

Our invention is fully illustrated in the accompanying drawings, in which Figure I is a

portion of our improved core having strips of whalebone at right angles to each other in 50 saw-kerfs in the rattan. Fig. II is the same with a semicircular piece removed, on the line *xx*. Fig. III is a transverse section. Fig. IV is a side view of a whalebone strip. Fig. V is an end view of the same. Fig. VI is a reduced view of a core, ready for covering. Fig. VII is a portion of a core having only one strip of whalebone, and Fig. VIII is a transverse section of the same.

a is the rattan, *b* is a saw-kerf therein, and 60 *d* is a strip of whalebone.

Although one strip of whalebone let into and secured in the rattan, as shown in Figs. VII and VIII, illustrates the principle of our invention in re-enforcing the elasticity and 65 strength of the rattan, we prefer to employ two strips, as shown in Figs. I, II, and III, the two strips intersecting each other at approximately a right angle, and at their intersection coinciding with the longer axis of the 70 rattan. In combining these two strips *d* one such, as seen in Fig. IV, is first inserted and glued in a saw-kerf in the rattan, and the rattan turned at right angles has formed in it another kerf through both rattan and 75 whalebone, to receive the other strip to complete the core.

It is advisable when two strips at right angles to each other are used to let one extend nearer to the butt of the whip, to prevent the whip when in use from bending too much at one point.

Now, having described our invention, what we claim is—

As an improved article of manufacture, a 85 whip-core consisting of a tapered rattan piece having longitudinal saw-kerfs and flat whalebone strips fitted into and secured in said kerfs by glue, substantially as described.

ROBT. M. WILSON.
EDWARD M. SPEAR.
MAYNARD F. PEIRCE.
